UNITED STATES PATENT OFFICE.

OSCAR OWENS, OF SAN FRANCISCO, CALIFORNIA, ASSIGNOR TO THE
AMERICAN TYPE FOUNDERS COMPANY.

IGNITER FOR EXPLOSIVE-ENGINES.

SPECIFICATION forming part of Letters Patent No. 605,333, dated June 7, 1898.

Application filed November 27, 1896. Serial No. 613,671. (No model.)

To all whom it may concern:

Be it known that I, OSCAR OWENS, a citizen of the United States, residing at San Francisco, in the county of San Francisco and State 5 of California, have invented certain new and useful Improvements in Igniters for Explosive-Engines; and I do hereby declare that the following is a full, clear, and exact description thereof.

10 My invention relates to electrical igniters for engines whose power is derived from successive charges of combustible gas or vapor.

One object of my invention is to avoid the use of springs or of other frail parts in the 15 combustion-chamber where such springs or other parts are commonly subjected to the excessive heat produced by the explosions and to place all springs, pivots, bearings, and parts exposed to wear outside of such chamber, where they can always be examined, removed, and replaced without difficulty and without removing cylinder-heads or valve-chest covers.

Another object is to provide means for 20 changing the time of ignition without stopping the engine, so that it can be made to take place at any time during the piston-stroke. By so regulating the ignition I can accomplish the best results as to power and efficiency with 25 minimum charge of explosive mixture.

Another object of the invention is to start 30 the engine quickly without being required to pull the fly-wheel through several revolutions. I am enabled to accomplish this last 35 object in a very simple way by means of the devices employed for regulating and changing the time of ignition, as referred to above.

My improvements, as I have herein described and shown them, are embodied in: a 40 single-cylinder vertical gas-engine of a well-known type. This kind of engine, however, is here employed only for the purpose of illustration, since my igniter and the means for operating and regulating it can be applied to 45 all kinds of explosive-engines.

This specification should be read in connection with the accompanying drawings, in which—

Figure 1 is a side elevation of gas-engine 50 with my improvements applied. Fig. 2 is a

front elevation of the same. Fig. 3 is an elevation of the valve-chamber, partly broken away to show the interior and a section of the covering-plate and also showing the connection by which the igniter is operated. Fig. 4 55 is a plan view of the covering-plate. Fig. 5 is a detail view of the means for adjusting the connections which operate the igniter. Fig. 6 is a detail elevation of the igniting-electrodes. Fig. 7 shows a modification in one of 60 the electrodes.

In the drawings I have illustrated so much of a gas-engine as will give a clear idea of the 65 rotation of my invention to such an engine.

A represents the cylinder; B the crank-shaft, C the connecting-rod; and D the valve-chamber, opening into the cylinder, and hence communicating with the combustion-space.

I prefer to attach my igniter to the cover-plate E of the valve-chamber and have so 70 shown it; but it can be applied instead to the cylinder-head, although the former location is preferable.

The igniter proper consists of two pivoted non-elastic terminal electrodes F and G. The 75 electrode F is keyed upon a hardened-steel pin 1, journaled in the plate E, and is of an angular or curved shape and provided with a rounded end 2, as shown in Fig. 6. The electrode G is keyed upon a similar pin 3, journaled in a thimble 4, the latter being insulated by a non-conducting bushing 5. A nut 6 on a threaded part of the thimble 4 draws the inner flange of said bushing against the cover-plate E and also holds in place the angle- 80 plate 7, Fig. 3. The electrode G is a flat tapered plate, with the edge of which the electrode F makes a direct contact about at right angles, Fig. 6. I may, however, provide the electrode G with a roller 8 at its extremity 85 to serve as the contact, and have illustrated such a modification in Fig. 7. Secured upon the outer end of the pin 3 is an arm or lever 9, the end of which has a loose bearing upon a pin 9, secured in the angle-plate 7, Fig. 4. 90 A spring 10 is interposed between the plate 7 and arm 8, which therefore holds the electrode G in normal position for contact with electrode F, but yields when the contact is made, as shown in dotted lines in Fig. 6. The 95

100

pin 9 has a head 11, which acts as a stop when the electrode G returns to normal position. The angle-plate 7 carries also a binding-post H for one of the battery-wires, the post I for the other wire being mounted at any suitable point on the cover-plate E, Fig. 2.

Upon the outer end of the journal-pin 1 is secured a lever 12, to which is connected a spring 13, which restores the electrode F to normal position after each contact, the lever 12 being arrested by a stop-pin 14, Fig. 4.

The parts so far described comprise the igniter proper, and it will be observed that the only parts exposed to heat within the explosion-space are of solid metal, without elasticity and without pivots or wearing parts of any kind. The operating connections on the outside, besides being in a comparatively low normal temperature, are further protected by a water-space in the cover-plate.

The oscillating electrode F, which is the circuit maker and breaker, is operated in one direction by connections which derive their movements from the engine-shaft and in the other by the spring 13, before referred to. The contact movement is directly produced by a push-bar J, which in a vertical engine like that shown derives its motions from a rod K through an intermediate bell-crank L. If the construction of the engine and location of the igniter admit of a direct action of the rod K upon the igniter-lever, the push-bar may be a continuation of such rod K and the bell-crank be dispensed with.

I shall hereinafter describe certain novel features in the transmission of motion to the rod K. It is sufficient at present to assume that it derives a reciprocating motion from the engine and communicates the same motion, whether directly or indirectly, to the push-bar.

Journalized in a stud 15 on the cover-plate is a spool-shaped roller 16, the flanges of which form guides for the push-bar, Figs. 3 and 4. The push-bar has a reduced end 17, which bears against the igniter-lever, and the main part of the bar merges into the reduced portion by a curve 18. The bar strikes the igniter-lever near the edge of the latter, moves it positively, and makes the contact, Fig. 6; but as the curve 18 immediately after bears upon the roller 16 the push-bar is thrown off the edge of the lever, permitting the springs 10 and 13 to act upon the separate igniter-levers 8 and 12. The lever 8 is, however, stopped by the bolt-head 11 before the lever 12 is arrested by the stop 14, and hence the electrodes are separated, producing the spark, and assuming the normal position of the full lines in Fig. 6. On the other edge of the push-bar is another curve 18^a, placed behind the curve 18, which enables me to change the time of ignition by reversing or turning the push-bar around so that the cam 18^a is brought in line with the spool, since the curve 18^a bears upon the spool and releases the igniter-lever a little later than the curve 18 would have done.

I now proceed to describe the connections

from the engine-shaft for operating the igniter and the adjustments and regulation of said connections to accomplish some of the objects referred to above.

The engine-shaft carries a gear M, which either directly or through intermediate gearing, such as N, communicates motion in the ratio of two to one to the gear O. This gear is mounted upon a shaft O', journaled in the engine-frame. Mounted loosely upon the shaft O' between its gear and the engine-frame is a cam P. The cam is mounted loosely, so as to be adjustable upon the shaft, but is held in place at any point of adjustment by a bolt 28, which passes through the cam and through a slot 19 in a plate Q, the latter being keyed to the shaft O' (lower part of Fig. 3.) A rocker R carries a roller 20, upon which the cam bears, and is pivoted to the lower end of the rod K, which operates the igniter, as before described. An adjustable lever S is pivoted at 21 to the engine and at 22 to the rocker R and at its upper end carries a spring-latch 23, adapted to engage with a toothed sector T, secured upon the engine. The latch thus locks the lever S, but permits its adjustment when the latch is disengaged from the sector. The operation of these connections will be readily understood. The cam is adjusted to proper position on its shaft and secured to the slotted plate Q, and then revolves regularly with the shaft, lifting the rocker and letting it fall alternately, and hence giving a regular reciprocation to the rod K, by which the igniter is operated. The slotted plate Q affords sufficient range to permit the cam to be adjusted so as to properly time the spark, and in addition the time of sparking can be changed by the adjustment of the lever S. This enables the spark to be produced at varying points in the piston-stroke and with varying charges of the explosive mixture, for by changing the position of the lever S relatively to the sector the cam is compelled to operate the rocker earlier or later, as the case may be, and this without stopping the engine.

It is also to be noted that the engine can be started without any laborious pulling of the fly-wheel through several revolutions. With the crank just past the center the battery can be cut out, stopping the engine. When ready to start, a partial turn of the fly-wheel will compress sufficient of the explosive charge to give the initial stroke. The battery can now be reconnected, and the engine is started by simply moving the lever S forward. The rocker-roller travels up the cam and operates the igniter, producing a spark which gives the initial explosion and an impulse to the piston, after which the engine continues in operation.

I do not desire to be limited in my patent to exact features of construction, which I have herein described and shown for the purpose of affording a practical embodiment of my invention, but not the only embodiment. Many modifications can be made by me or by

others skilled in the art which will be equivalents of those described and shown within the scope afforded by the following claims.

Having thus described my invention, what I claim as new, and desire to secure by Letters Patent, is—

1. In an igniter for explosive-engines, the combination with two pivotal terminal electrodes having returning-springs, and operating arms or levers, of a reversible push-bar, having cam curves on opposite edges placed out of line with each other, a guide-roller for said push-bar, and connections from the engine-shaft for operating said push-bar, substantially as described.
2. In an igniter for explosive-engines, and in combination, movable igniting-electrodes, a rod for operating said electrodes, a cam mounted on a geared-down shaft, for operating said rod, and means for adjusting the end of said rod relatively to the cam, in order to vary the time of its operation by the cam, substantially as described.

3. In an explosive-engine having an electrical igniter, a shaft geared down from the engine-shaft, a cam mounted upon said shaft, a rod connected to the igniter, an adjustable lever, means for locking said lever in different adjustments, and a connection from said lever to the said rod, adapted, by the adjustment of said lever, to be placed in different positions relatively to the cam, whereby the time of ignition can be changed, substantially as described.

4. In combination with a cam and rod for operating an electrical igniter, a lever connected to said rod, a latch carried by said lever, and a toothed sector for locking said latch and lever, substantially as described.

In testimony whereof I have affixed my signature, in presence of two witnesses, this 17th day of November, 1896.

OSCAR OWENS.
